HOMER P. CHANDLER, OF MANSFIELD, OHIO, ASSIGNOR TO THE OHIO BRASS COMPANY,
OF MANSFIELD, OHIO, A CORPORATION OF NEW JERSEY

CONDUCTOR SUPPORT

Application filed June 26, 1930. Serial No. 463,915.

My invention relates to supporting devices for conductors and has particular reference to trolley and feeder conductors in mines.

One object of my invention is to provide a device which will support not only the trolley conductor but the feeder conductor therefor and in which the device will act as an equalizer between the two conductors. Another object is to provide a device with clamping arrangement which will accommodate a wide range of feeder conductors as well as a considerable range of trolley conductors thus economizing in the number of devices a mine would be obliged to carry to meet its requirements. Another object is to provide a device with clamping mechanism for the conductors which will open by gravity and therefore does not require holding the clamping mechanisms open while installing the conductors. A still further object is to remove the feeder conductor away from the trolley conductor as far as possible within reason, thereby lessening the chances of the flying trolley pole becoming entangled with the conductors.

My invention resides in the new and novel construction, combination and relation of the various parts hereinafter described and shown in the drawing.

In the drawing:—

Fig. 1 is a side view in elevation and partial section of my invention.

Fig. 2 is a top plan view of my invention shown in Fig. 1.

In the preferred embodiment of my invention I employ a socket 1 internally threaded as indicated at 2 to receive a hanger or other supporting device. Projecting laterally and at right angles to the axis of the socket 1 is a straight arm 3 having at the free end a tubular portion 4 which has a passage therethrough comprising a part 5 of less diameter than the part 6. Projecting inwardly at the lower end of the member 4 is an annular flange 7.

Mounted within the tubular member 5 and projecting from both ends thereof is clamping mechanism comprising a pair of jaws 8 having co-operating lips 9 to receive and grip a trolley wire 10. The jaws are hinged together by means of a pintle 11 and secured to

the pintle 11 is a threaded stud 12 having mounted thereon the threaded nut 13 engaging the upper end of the member 4. It will be noted that the mechanism comprising the parts 8, 11 and 12 are quite free to move axially or up and down within the tubular member 4 and that the downward movement of the said parts are limited by the nut 13. The downward movement of the parts is due to gravity.

The upper end of the jaws 8 at their outer edges are each provided with an arcuate groove 14 which receives the annular flange 7. The jaws and stud 12 are free to rotate about their vertical axis within the member 4, but the interlock between the jaws and the flange 7 will cause the jaws to fulcrum with respect to the flange 7 such that as the nut 13 is moved upwardly on the stud 12 and the clamping mechanism is therefore free to move downwardly, the jaws will fulcrum or pivot about the flange 7 and the lower end of the jaws 8 will separate or open to receive the trolley conductor 10.

From this it will be noted that having the jaws open it is very simple for an operator with one hand to place the trolley wire 10 in position between the jaws and with the other hand to rotate the nut 13 to cause it to move downwardly relative to the stud 12 thus drawing the stud 12 upwardly and with it the hinge point of the jaws thus causing the jaws to fulcrum about the flange 7 and forcing the lower end of the jaws together and with gripping engagement with the conductor 10. A wrench may then be applied to the nut 13 which will make the grip positive.

Also projecting from the socket 1 there is a downwardly and outwardly formed arm 15 and having an integrally formed jaw 16 having a groove 17 to receive the conductor 18. Pivoted secured to the free end of the arm 15 by means of the pin 19 is a movable jaw 20 so constructed that if unrestrained its free end will move away from the jaw 16 by gravity. The jaw 20 is provided with a groove 21 preferably V shaped. The movement of the jaw 20 relative to the jaw 16 is controlled by means of the bolt and nut 22

disposed in transverse openings 23 and 24 of the jaws 16 and 20 respectively.

The free end of the arm 15 is in a horizontal plane below, but parallel to a horizontal plane of the arm 3 and the conductor 18 is positioned in a horizontal plane parallel to that of the plane of the arm 3, but above the same and also above a horizontal plane of the conductor 10.

10 There will be modifications which will suggest themselves to those skilled in the art after reading my disclosure and therefore I wish to be limited only by my claims.

I claim:—

15 1. A support for conductors comprising a body member having means intermediate its ends to secure it to a hanger and means at each end to receive conductors, the means at one end comprising a tubular shaped portion with inwardly projecting flange at one end, a pair of hinged jaws interlocked with the flange, co-operating means on each jaw to receive and grip a conductor and means pivotally secured to the jaws and projecting 20 through the said tubular portion and means threadably mounted on the projecting means and engaging the tubular portion to force the clamping end of the jaws into engagement with the conductor, when rotated and 25 the means at the other end of the body comprising a fixed and a movable jaw, each having co-operating means to grip a conductor and transversely disposed means to engage the last said clamping means to draw 30 the said means into contact with the conductor.

2. A support for conductors comprising a body member having a threaded jaw to receive a hanger, a tubular portion at one end 40 of the body member to receive an externally threaded stud of a conductor clamp, a pair of co-operating jaws pivotally secured to one end of the stud and interlocked with a flange on the tubular portion to hold a part of the 45 jaws substantially stationary, lips on the jaws to receive and grip a conductor and rotatable means on the threaded stud to move the stud to open or close the jaws relative to the conductor, an upstanding portion on the opposite end of the body 50 and integrally formed thereon, a pivotally mounted member at the base of the upstanding portion and co-operating grooves on the upstanding portion and the pivotal member to receive a conductor and means to move the pivotal member to grip the conductor.

3. A support for conductors comprising a tubular member having a passage enlarged at one end and reduced at the other end, an 60 inwardly projecting annular flange at the enlarged end, a pair of jaws mounted in the tubular member and projecting therefrom and having means to receive the said flange, a threaded stud mounted in the tubular member and projecting therefrom, a pintle to

pivots to secure the jaws and stud together, means on the jaws to co-operate to receive and clamp a conductor and means on the stud to engage the tubular member to operate the jaws into gripping engagement with the conductor, an arm projecting laterally from the tubular member and means on the arm to secure it to a hanger.

4. A support for conductors comprising a tubular member having a passage enlarged at one end and reduced at the other end, an inwardly projecting annular flange at the enlarged end, a pair of jaws mounted in the tubular member and projecting therefrom and having means to receive the said flange, a threaded stud mounted in the tubular member and projecting therefrom, a pintle to pivotally secure the jaws and stud together, means on the jaws to co-operate to receive and clamp a conductor and means on the stud to engage the tubular member to operate the jaws into gripping engagement with the conductor, an arm projecting laterally from the tubular member and means on the arm to secure it to a hanger. 75

5. A support for conductors comprising a tubular member, a pair of jaws and a threaded stud hinged together and mounted within the tubular member, a nut on the stud to draw the stud and hinged portion of the jaws into the tubular member to close the jaws, fulcrum means on each jaw spaced from the hinged portion to engage with the tubular member, co-operating means on the jaws to grip a conductor, a lateral arm projecting from the tubular member, a supporting member on the end of the arm to receive a hanger, a drop-arm projecting from the supporting member, an upstanding member at the free end of the drop-arm and integrally formed thereon, a second upstanding member pivotally secured to the drop-arm at the base of the fixed member, the pivotal point being in a plane below that of the lateral arm, co-operating means on the upstanding members to grip a second conductor and means to move the upstanding members together to grip the conductor.

6. A supporting device for conductors comprising a support member to receive a hanger, a straight arm and a drop-arm projecting from the support member from opposite sides thereof, a clamping mechanism for a trolley wire at the free end of the straight arm and a clamping mechanism for a feeder from the free end of the drop-arm, the latter clamping mechanism comprising a pair of upstanding jaws, one fixed to the drop-arm and the other pivotally secured thereto and the jaws having co-operating means to grip the feeder and means disposed in alignment with the straight arm to move the pivotal jaw to grip the feeder.

7. A supporting device comprising a support member, a horizontally disposed arm projecting from the support member, a second arm projecting from the support member and having its free end in a plane below the horizontal plane of the first arm, a clamp positioned at the free end of the first arm and having a longitudinal axis at right angles to the said horizontal plane and having means to grip and hold a trolley wire in a plane below and spaced from the said horizontal plane and a clamp positioned at the free end of the second arm and having its longitudinal axis at right angles to the said horizontal plane and having means to grip and hold a conductor in a plane above and spaced from the horizontal plane.

8. A supporting device comprising a tubular member having a two part continuous passage therethrough in which one part is of larger diameter than the other part and an inwardly projecting flange at the larger part, clamping mechanism slidably mounted within the tubular member and free to move downwardly by gravity and to open to receive a trolley wire as it moves downwardly by gravity, the said mechanism comprising a pair of clamping jaws having co-operating clamping means at one end, a threaded stud extending through and beyond the smaller passage in the tubular member, the jaws and stud hinged together at a common point and means on each jaw to engage the flange and form a fulcrum point therewith about which the jaws pivot when they move downwardly or upwardly to open or close the jaws respectively and a threaded member mounted on the stud and engaging the tubular member to support the clamping mechanism and limit its downward movement and to move it upwardly and into clamping relation with the trolley wire when the threaded member is rotated and means secured to the tubular member to receive a hanger to support the supporting device.

9. A supporting device comprising a threaded socket to receive a hanger, an arm projecting laterally therefrom, an arm projecting downwardly and away from the socket, a clamping mechanism secured to the first arm to open by gravity and receive and grip a conductor below the said arm, a clamping mechanism secured to the second arm to open by gravity and receive and grip a conductor above the said arm.

55 In testimony whereof I affix my signature.
HOMER P. CHANDLER.
